H. L. PINTLER

GAME

Filed Oct. 22, 1921

FIG. 1.

FIG. 2.

FIG. 3.

Inventor.

H. Lewis Pintler.

Atty.

UNITED STATES PATENT OFFICE.

HOWARD LEWIS PINTLER, OF PEORIA, ILLINOIS.

GAME.

Application filed October 22, 1921. Serial No. 509,577.

To all whom it may concern:

Be it known that I, HOWARD LEWIS PINTLER, a citizen of the United States, and a resident of Peoria, in the county of Peoria, 5 State of Illinois, have invented certain new and useful Improvements in Games, of which the following is a full, clear, and exact description, reference being had to the accompanying drawing, forming part of this 10 specification.

My invention relates more particularly to games similar to quoits wherein the players stand at a distance from a stake and pitch or toss articles toward the stake, the 15 counting being determined by the nearness of the articles to the stake.

Such games have been played by using cast off horse shoes, which are usually rough and have sharp edges, and are 20 inconvenient to hold or pitch.

The object of my invention is to provide an article, similar in shape and size to a horse shoe, but arranged to be easily held and pitched without liability of tearing or 25 wearing the skin from the fingers of the player.

The novelty of my invention will be hereinafter more fully set forth and specifically pointed out in the claims.

In the accompanying drawing:

30 Fig. 1 is a perspective view of a game device made in accordance with my invention.

Fig. 2 is a plan view of Fig. 1.

Fig. 3 is an edge view of Fig. 2.

35 The same numerals of reference are used to indicate identical parts in all the figures.

In carrying out my invention I provide a

device somewhat in the form of a horse shoe and comprising a curved body portion 1 provided with lugs 2 and 3 similar to heel calks, and a third lug 4 similar to a toe 40 calk.

The body portion is widened on one side as shown at 5, and the lug of the calk 3 is concaved across its face as shown at 6, the concave portion and the widened portion 5 45 serving as means for holding the device, the second joint of the index finger resting in the concave portion 6 while the thumb and the second finger rest above and below the widened portion 5.

The edges of the concave portion 6 are 50 preferably rounded as shown at 7, Fig. 2, so that as the device is pitched, it can be released without danger of injury to the player.

Having thus fully described my invention, I claim:

1. In a game device a curved body portion, a projection at that end of the body portion grasped for throwing and provided 60 with a concave face, and a widened portion of uniform thickness with the body portion and adjacent the end of the body portion which carries the concave face projection.

2. In a game device the combination of 65 a horse shoe shaped body, calks carried thereby, one of said calks being concave faced to afford a finger hold for throwing, and a thumb and finger holding portion projecting inwardly from the body portion and 70 adjacent the calk which is concave faced.

H. LEWIS PINTLER.
